UNITED STATES PATENT OFFICE.

JOHN W. KIDWELL, OF HARTFORD, CONNECTICUT.

SMOKER'S APPLIANCE.

Application filed March 10, 1922. Serial No. 542,704.

To all whom it may concern:

Be it known that I, JOHN W. KIDWELL, a citizen of the United States, residing at Hartford, in the county of Hartford and 5 State of Connecticut, have invented certain new and useful Improvements in Smokers' Appliances, of which the following is a specification.

This invention relates to a smoker's appliance and while the article can be employed with decided advantage in many different connections, it is, however, of especial utility when used in conjunction with a pipe. In this connection, usually in the form of a 15 plug, it is inserted into the bowl of a pipe and is of such a character that it can receive and absorb nicotine and such deleterious substances so that the smoke will enter the mouth in a clean and dry condition. In addition to this, the bowl of the pipe or equivalent article will be left free of objectionable matter and on the contrary will be dry and clean.

In the drawing accompanying and forming part of the present specification, I have shown in detail, one of the several convenient forms of embodiment of the invention which to enable those skilled in the art to practise the same will be set forth fully in 25 the following description. Obviously I am not restricted to this disclosure. I may depart therefrom in a number of respects within the scope of the invention defined by the claim following said description.

30 Referring to said drawing:

Fig. 1 is a sectional side elevation of a pipe provided with a smoker's appliance involving the invention.

Fig. 2 is a cross section on the line 2—2, 40 Fig. 1, looking toward the right.

Figs. 3 and 4 are perspective views of the appliance as seen respectively from below and above.

Like characters refer to like parts 45 throughout the several views.

As I have already noted the appliance can be used with advantage in several ways, although it is of especial utility when associated with a pipe. In this event, it is preferably placed in the bottom of the bowl 50 thereof.

In Figs. 1 and 2, I have shown a pipe of ordinary construction which comprises the bowl 2 and the stem 3, the stem having the 55 smoke passage 4 longitudinally thereof and

which opens into the lower side of the chamber 5 of the bowl. This chamber tapers downwardly and is intersected at its lower end by the forward end of the smoke passage as is quite common in smoking pipes 60 of various styles.

The nicotine absorber is denoted in a general way by 6 and fits closely or solidly in the bottom of the chamber 5. I prefer to make the absorbing element 6 in the form of 65 a plug of some nicotine absorbing material such as a high-grade clay. This plug as I have observed, fits closely in the bottom of the chamber 5 as shown in Figs. 1 and 2 and it supports upon its upper surface which is 70 generally flat, the mass of tobacco which is to constitute the charge 7.

The plug 6 has as shown in its lower side, the channel 8 which when the plug is in the bowl, extends from the front to the rear 75 so the channel is thus put into direct communication with the smoke passage 4. In addition to this said plug has a depthwise extending port 9 which cuts the channel 8 about centrally thereof and which centrally 80 intersects the upper surface of the plug 6.

In use the plug 6 is closely fitted in the bottom of the bowl 2 at which point a charge of tobacco as 7 is laid upon the plug. The charge is then lighted and the pipe is 85 smoked. The smoke passes down through the port 9 through the channel 8 and along the smoke passage 4. The plug absorbs all nicotine so that the smoke enters the mouth of the smoker in clean, dry and sweet condition. 90

I prefer that the plug 6 be used generally for a short time, usually for a day or two. When it is entirely impregnated with nicotine, it can be readily and quickly discharged by tapping the bowl 4 upon the bottom thereof at which time a fresh one will be put in the pipe bowl. 95

What I claim is:

A smoker's appliance comprising a frusto-conical plug of clay, having a channel extending entirely across its under side, the upper face of the plug being flat, the plug having a port leading centrally from said flat surface to and intersecting the passage. 100

In testimony whereof I affix my signature.

JOHN W. KIDWELL.
